Patented July 25, 1922.

UNITED STATES PATENT OFFICE.

OGDEN F. BLYBURG, OF ST. JOSEPH, MICHIGAN.

SHOCK ABSORBER.

1,423,904.

Specification of Letters Patent. Patented July 25, 1922.

Application filed February 16, 1921. Serial No. 445,278.

To all whom it may concern:

Be it known that I, OGDEN F. BLYBURG, of St. Joseph, Berrien County, Michigan, have invented a certain new and useful Improvement in Shock Absorbers, of which the following is a specification.

This invention relates to shock absorbers in general, but more particularly to those having a dash pot action to cushion the load weight, or the impact of the shock, in conjunction with one or more springs.

Generally stated, the object of the invention is to provide an improved and novel construction whereby a dash pot, or several of them, may be advantageously combined with spring means to cushion the shocks on an automobile, or on a railway car, or in other places, as will hereinafter more fully appear.

To these and other useful ends the invention consists in matters hereinafter set forth and claimed, and shown in the accompanying drawings, in which:

Figure 1 is a longitudinal section of a shock absorber embodying the principles of the invention.

Figure 2 is a vertical transverse section on line 2—2 in Figure 1.

As thus illustrated, the invention comprises a housing 1 of metal plates secured together in the manner shown to form a box of rectangular form. The cylinders 2 are secured in said housing, to the base thereof, as shown, and provided at the base thereof with ports or passages 3 to admit oil from the housing, and to permit the return of the oil to the housing when the plungers 4 move downward in said cylinders 2, which latter with their plungers form dash pots. Said plungers have stems 5 to the upper ends of which a plate 6 is secured. A helical or coil spring 7 is coiled around each cylinder 2 to rest on the base thereof, and to bear against the under side of said plate 6, whereby downward movement of said bar not only drives the oil out of said cylinders 2, but also compresses said springs, which latter are immersed in the oil. Rods 8 are attached to the plate 6 and work up

and down in stuffing boxes 9 which seal the top of the housing. Springs 10 are interposed between the plate 6 and the bottom of the top wall of the housing, to cushion the upward movement of the plungers and other movable parts. Plugs 11 and 12 are pro-

vided in the housing for the admission and discharge of the oil when necessary. The walls of the housing are all removably held together by bolts 13 or any other means.

The dash pot and housing may be used, of course, without the springs, in any suitable or desired manner. When the load weight on the rods 8 moves the plungers downward, then the oil is driven out of the cylinders 2 and into the housing. Sufficient oil is maintained in the structure to nearly fill the housing when the plungers are down. When the load weight rises, because of the upward pressure of the springs 7, or any other provision, the oil is sucked back into the cylinders. As everything is enclosed, and immersed in the oil, there is less danger of rusting or deterioration or other similar trouble. The device as thus constructed can obviously be used on automobiles, or motor trucks, or in other places, and is sealed against the admission of dirt or dust, and against leakage of the oil. Any number of dash pots can be used, of course, without departing from the spirit of the invention.

From the foregoing it will be seen that the cylinders 2 forming the dash pots serve to keep the springs 7 in place, and form guides therefor, so that said springs do not rub against each other or against the housing, there being clearance all around the springs for this purpose.

What I claim as my invention is:

1. A shock absorber comprising a plunger, a chamber in which said plunger is arranged to reciprocate, forming a dash pot, and spring means held in place by the dash pot and adapted to yieldingly hold said plunger in normal position.

2. A structure as specified in claim 1, in combination with a housing for enclosing the spring means and adapted to contain a liquid for said dash pot, with said dash pot forming a guide for said spring, and with a passage connecting said chamber with said housing, so that the liquid flows back and forth between the housing and the chamber, the spring means being immersed in the liquid.

3. A structure as specified in claim 1, in combination with a housing for enclosing the spring means and holding a quantity of liquid for said dash pot, with a passage connecting the chamber with the housing, so that the liquid flows back and forth between

the housing and the chamber, a rod for said plunger, and a stuffing box in which said rod slides, and whereby the housing is sealed.

- 5 4. In a shock absorber, a housing to contain a liquid, a cylinder in said housing, a plunger in said cylinder, with a passage connecting the cylinder with the housing, so that the liquid flows back and forth between
- 10 the housing and the chamber, a coil spring arranged for compression on the exterior surface of said cylinder, means connected to said plunger to bear upon said spring, so that the spring is compressed when the
- 15 plunger expels the liquid from said chamber, with clearance all around to prevent the spring from rubbing on the housing, a stuffing box on the housing, and a rod connected to said plunger to slide in said
- 20 stuffing box.
5. A structure as specified in claim 4, and a smaller spring on said rod to limit the return movement of the plunger.
6. A structure as specified in claim 4, said
- 25 spring being immersed in the liquid in said housing.
7. A structure as specified in claim 1, said spring being coiled around said dash pot to slide up and down thereon.
- 30 8. In a shock absorber, a cylinder and plunger forming a dash pot, a spring coiled around said cylinder, so that the dash pot is enclosed by and forms a guide for said spring, and means rigid with said plunger

to compress said spring when the plunger moves into the cylinder.

9. A structure as specified in claim 8 in combination with one or more similar cylinders and plungers each forming a dash pot with a spring thereon, the springs being spaced apart to prevent them from interfering with each other, the housing enclosing said dash pots and springs, with clearance all around to prevent the springs from rubbing on the housing, and a liquid in said housing, the cylinder of each dash pot having a passage for the liquid.

10. A structure as specified in claim 8, and a housing spaced from said spring and adapted to contain a liquid, said cylinder having a passage for said liquid.

11. In a shock absorber, a plurality of cylinders, a plunger for each cylinder, coil springs enclosing said cylinders, so that each cylinder forms a guide for its allotted spring, a bar connecting said plungers and bearing upon said springs and means for communicating pressure to said bar, said springs being spaced apart to prevent them from interfering with each other.

12. A structure as specified in claim 11, and a housing for enclosing said springs and other elements, adapted to contain liquid, with a liquid inlet and outlet for each cylinder, and with clearance all around to prevent said springs from rubbing on the housing.

OGDEN F. BLYBURG
